UNITED STATES PATENT OFFICE.

ERNEST D. ANDERSON AND CARL BECKMANN, OF NEW YORK, N. Y., ASSIGNEES TO E. D. ANDERSON, INC., OF NEW YORK, N. Y., A CORPORATION OF NEW YORK.

LABELING MACHINE.

Application filed February 27, 1920. Serial No. 361,672.

To all whom it may concern:

Be it known that we, ERNEST D. ANDERSON, a citizen of the United States, and resident of New York city, borough of Manhattan, county and State of New York, and 5 CARL BECKMANN, a subject of Germany, and resident of New York city, borough of Queens, State of New York, have invented certain new and useful Improvements in 10 Labeling Machines, of which the following is a specification.

The object of this invention is to provide means to apply labels in a successive manner upon receptacles or containers for goods, 15 such as upon bottles.

This invention comprises means to supply receptacles or containers successively, means to apply adhesive or paste successively to the receptacles or containers, means to apply labels successively upon pasted portions of 20 receptacles or containers, and means to deliver the labeled receptacles or containers.

This invention further comprises novel details of improvement and combinations of 25 parts that will be more fully hereinafter set forth and then pointed out in the claims.

Reference is had to the accompanying drawings forming part hereof wherein—

Figure 1 is a side elevation of a machine, 30 a portion of the label applying parts being omitted.

Fig. 2 is a plan view;

Figs. 3 and 4 are enlarged detail views of 35 a portion of the conveyer for the containers; Fig. 5 is an enlarged cross section sub-

stantially on the line 5—5 in Fig. 1;

Fig. 6 is an end view of a portion of the machine looking at the left of Fig. 1;

Fig. 7 is an enlarged cross section sub- 40 stantially on the line 7—7 of Fig. 1;

Fig. 8 is a detached perspective view of the discharge guide for the labeled containers;

Fig. 9 is an enlarged plan view of a maga- 45 zine for the labels;

Fig. 10 is a longitudinal section of Fig. 9;

Fig. 11 is a cross section illustrating the position of the parts when the labels are being applied to the receptacles;

Fig. 12 is a plan view of part of Fig. 11;

Fig. 13 is a view illustrating the labels applied on the receptacles but before the labels are finally affixed thereto;

Fig. 14 is a cross section substantially on the line 14—14 in Fig. 2;

Figs. 15 and 16 are detail sectional views illustrating means for applying adhesive to the receptacles;

Fig. 17 is a detail section illustrating the position of parts with the labels being applied to the receptacles;

Fig. 18 is a detail sectional view illustrating different positions of means for finally affixing the labels on the receptacle; and

Fig. 19 is a perspective view of a receptacle showing a label applied thereto.

Similar numerals of reference indicate corresponding parts in the several views.

In the accompanying drawings the nu- 70 meral 1 indicates the main frame of the machine, the same being shown provided with legs 1^a and a table-like portion 2 having up-

rights 3 at opposite ends of the machine. A conveyer is indicated at 4, shown in the 75 form of an endless chain, having spaced stops or receivers 5 to propel receptacles or containers A on and with the conveyer. The stops or receivers 5 are shown in the form

of plates or blocks secured upon the blocks 80 4^a of the conveyer, as by rivets or screws 6, (Figs. 3 and 4). The conveyer is shown

passing over idle sprocket wheels 7 jour- 85 nalled upon uprights 3, over sprocket wheel 8 journaled upon bracket 8^a hung from ta-

ble 2 and over a sprocket wheel 9 loose on a shaft 10 shown journaled upon legs 1^a. Shaft 10 is provided with a gear 11 in mesh

with drive pinion 12 carried by drive shaft 13 journaled upon legs 1^a and having a pul- 90 ley 14 receiving belt 15 from a suitable source

of power for driving the machine. In the example illustrated the conveyer is oper- 95 ated step by step, for which purpose shaft 10 is provided with a gear wheel 16 in mesh with a gear 17 secured to shaft 18, (Fig. 1),

shown journaled in bearings in brackets 19 secured to and depending from table or plate 2, (Fig. 5). Said shaft is provided with

arm 20 having projection 21 adapted to op- 100 erate in radial slots 22^a in member 22 loose on shaft 10 and secured to sprocket 9, mem-

bers 21, 22 comprising operative members of a Geneva movement. As arm 20 is continu- 105 ously rotated the member 22 with sprocket 9 by means of engagement of projection 21 with slots or recesses 22^a will be rotated step

by step to correspondingly operate the conveyer. The machine is not limited to operation of the conveyer by the step by step means described.

5 The upper run of the conveyer travels within a guide-way for the receptacles A, which guide-way is shown comprising a bottom member or plate 23 and spaced side members or rails 24, the upper portion of 10 the conveyer being slidably supported on plate 23 and kept from lateral movement between the side members or rails 24. The upper inner edges of the side members or rails 24 are shown reduced or inwardly tapering at 24^a and the upper edges of side members 24 are above the top of the conveyer whereby the receptacles A on the conveyer will be slidably guided between the reduced portions 24^a of the side members for 15 retaining said receptacles in proper position as they are propelled, and for exposing the sides of said receptacles in position to receive the labels B.

The receptacles A may be supplied to the 20 conveyer in successive manner by any suitable means. We have shown a chute or guide-way 25 supported by the main frame and having its lower delivery end attached by the bracket 26 to the adjacent side member 24, the upper edge of which is reduced at 27 25 at the delivery end of said chute to permit the passage of receptacles A across said side member 24 to position upon the conveyer, (Figs. 2, 6, 14). At 28 (Fig. 14) is a stop 30 upon the side member 24 opposite the chute to cause the receptacles to abut to position them upon the conveyer. With a continuous supply of receptacles in chute 25 said receptacles will pass upon the conveyer successively as the conveyer carries them along 35 one after another.

After the receptacles have been deposited upon the conveyer suitable adhesive or paste is applied to the side or sides of the receptacles upon which a label or labels is or are to be fastened. In the example illustrated means are provided for applying adhesive and labels on opposite sides of the receptacles. A receptacle or tank 29, open at the 40 top, is mounted upon table 2 below the upper run of the conveyer and contains rollers 30 having shafts journalled upon said receptacle and provided with intermeshing gears 31, (Fig. 2), for rotating said rollers together. Upon the shaft of one of the rollers is secured a sprocket wheel 32 receiving an endless chain 33 from a sprocket wheel 34 secured upon shaft 35 journalled in suitable bearings upon the main frame. Shaft 35 45 may be driven by means of a bevel pinion 36 secured on said shaft and meshing with a bevel gear 37 secured on shaft 10, (Fig. 1). Over the corresponding rollers 30 are mounted laterally movable adhesive distributing members or rolls 38 which are journalled 50

upon rods or shafts 39 carried by reciprocative rods 40 guided in bearings 41 carried by table 2 on opposite sides of the conveyer. The rods 40 are connected together by a bar 42 (Fig. 5), shown pivotally 55 connected by a link 43 with a bell-crank 44 pivotally supported at 45 upon a bracket 46 hung from the main frame. Said crank is shown pivotally connected with a rod or link 47 the outer end of which is shown forked at 47^a and slidably upon shaft 35 which guides the rod or link. Said rod or link is provided with a projection 48 co-operative with a cam 49, as with a cam groove 49^a in the face thereof, for reciprocating said link, 60 whereby the crank 44 will be rocked to reciprocate rods 40 and rollers 38. Said rollers descend and encounter the corresponding rotating rollers 30 and receive adhesive or paste therefrom. In order to cause rotation of the rollers 38 independent of rotation of the same by contact with rollers 30, the shafts of rollers 30 are provided with knurled wheels 30^a that engage the corresponding rollers 38 for rotating the latter. 65 The rollers 38 are raised on opposite sides of the conveyer to encounter pasters 50 which are disposed on opposite sides of the receptacle A when it is brought to rest by the conveyer to receive the adhesive. The pasters 50 may comprise suitable supports 50^a having pads 50^b to engage rollers 38 to receive adhesive therefrom and to apply the adhesive to the sides of receptacle A. Supports 50^a are shown provided with outwardly extending rods 51 slidably in heads 52 carried upon bars 53 supported on opposite sides of the conveyer. Springs 51^a are shown interposed between the pasters 50^a and the heads 52 to normally push the pasters 50 70 outwardly, pins 51^b in the rods 51 engaging the heads 52 to limit such movement of the pasters, (Figs. 2 and 5). The pads 50^b thus are caused to engage receptacles A in a resilient manner by reason of spring pressure 75 against said pads. Said bars are shown provided with spaced guides 54 slidably mounted upon transverse rods 55 secured upon uprights 56 on the main frame, (Fig. 5), as by brackets 57 attached to table 2. Bars 53 are 80 adapted to be moved toward and from the conveyer. Shafts 58 are journalled in the spaced uprights 56 on one side of the machine, the upper ends of said shafts being provided with arms 59 projecting on opposite sides of the shafts, (Fig. 4). One end of each of said arms is pivotally connected with a link 60 that is pivotally connected at 61 with the adjacent bar 53, and the other ends of said arms 59 are pivotally connected with links 62 which extend across the machine pivotally connected at 63 with bar 53 on opposite sides of the machine, (Fig. 4). The lower end of one of the shafts 58 85 is provided with a crank arm 64 that is piv- 90

totally connected by link 65 with crank arm 66 on the other shaft 58 whereby said shafts may be rocked equally in unison. As shafts 58 are rocked the bars 53 will be caused to 5 approach and recede to correspondingly operate the parts carried by said bars. The shaft 58 having crank arm 64 is also provided with a crank arm 67 pivotally connected with rod 68, (Fig. 5), the opposite end of 10 which rod is shown slotted at 68^a and slidably guided thereby upon shaft 35. Said rod is provided with a projection 69 co-operative with a cam 70 shown in the form of a groove 70^a in the face of said cam, (Fig. 15), whereby as said cam is rotated shaft 58 will be rocked to correspondingly cause the bars 53 to approach and recede. When the bars 53 with the pasters 50 thereon come to 15 rest in a spread position the rods 40 rise and 20 elevate the rollers 38 into engagement with the outer faces of pads 50^b to apply adhesive thereto, (Fig. 15). Said rollers next descend out of the path of said pads and thereupon the bars 53 are operated to approach 25 the conveyer so that the pads 50^b with adhesive on their forward faces will engage a receptacle A then at rest upon the conveyer between said pads to apply adhesive to the opposite sides of said receptacle, 30 (Fig. 16). Said bars 53 and pasters will next recede. Said operations occur successively for each receptacle brought to rest between the pasters 50.

After adhesive or paste has been applied 35 upon the sides of the receptacles the latter are stepped along with the conveyer and are brought to rest between opposing magazines 71 containing the labels B. Said magazines are shown in the form of troughs 40 open at the tops and at opposing ends and are secured upon the bars 53 on opposite sides of the conveyer. The delivery ends of the magazine are shown provided with inturned stops or lugs 72 in the path of the 45 labels, (Figs. 2, 9 and 12), whereby the end-most labels are retained at the ends of the magazines. A head or plunger 73 in each magazine bears against the inner portion of the stack of labels therein, which head or 50 plunger is upon a rod 74 projecting rearwardly through a glide-hole in the rear wall 71^a of the magazine, (Fig. 11). A spring 75 shown coiled around rod 74 bears at one end against head or plunger 73 and 55 at the opposite end against wall 71^a and serves normally to push the head resiliently against the stack of labels with the tendency to push said labels from the magazine. The faces 73^a of heads or plungers 73 which 60 oppose the labels are shown curved or protruding in form, having the effect to cause the labels B to protrude centrally in a convex or curved form, (Figs. 2 and 9), so that the outermost labels may engage the sides 65 of the receptacles A when the magazines con-

taining the labels are pushed close to the receptacles, (Fig. 12).

Means are provided to control the feeding operation of the labels in the magazine as follows:—A gripper 76 is mounted upon the corresponding rod 74, being shown in the form of a block having a hole 76^a snugly receiving said rod, (Fig. 11), which block is pivotally supported upon the corresponding magazine, (Figs. 10 and 11). The magazine is shown provided with spaced arms 77 receiving the gripper 76 therebetween, which arms support pivot pins 78 extending from the gripper block, (Fig. 9). The arrangement described is similar for each 75 magazine. The gripper blocks have arms or projections 79 connected by springs 80 with a corresponding bar 53, (Figs. 10, 11, and 17), which springs tend to tilt the gripper blocks 76 to grip the corresponding rod 85 74 to prevent operation of the latter and plunger 73 by spring 75 until the proper time. The arms or projections 79 are in the path of a corresponding stop 81 shown carried by upright 82 secured upon table 2, 90 (Figs. 5, 11 and 17). Stops 81 are shown in the form of screws retained by nuts 83, whereby said stops are adjustable with respect to the moment of engagement therewith of the corresponding arms or projections 79. When the bars 53 are spread apart 95 (Fig. 5) the magazines 71 and labels will be correspondingly spread with said bars.

When the conveyer comes to rest with a pasted receptacle A between magazines 71 100 the bars 53 will approach, in manner before described, and the endmost labels will be pushed against the pasted sides of the receptacle, (Fig. 11), as the magazines approach the limit of their travel toward the 105 receptacle. Arms or projections 79 (whose blocks 76 then retain plunger 73 from movement) will engage a corresponding stop 81, whereby continued movement of the magazines toward the receptacle will cause the 110 grippers 76 to be tilted and release rods 74, permitting the springs 75 to push the plungers 73 with the labels B toward the receptacle, (Figs. 11 and 17), whereby the rods 74 are fed through the grippers 76, and 115 the magazines come to rest. As the magazines with the labels next recede the endmost labels that are in engagement with the paste on the receptacle A will adhere to the sides thereof, (Fig. 12), and the ends of 120 said labels will slip or snap past the lugs 72 to be withdrawn from the magazines and remain adhering to the receptacle, (Fig. 13). As the magazines recede from the receptacle 125 springs 80 will cause gripper blocks 76 to tilt on their pivots to grip the corresponding rods 74 to retain the latter and the plunger as the arms or projections 79 pass from the stops 81, so that the plungers will not push the remaining labels from the magazines, 130

and the outermost labels will assume positions with their ends caught behind the lugs 72. The foregoing operations of applying labels to the receptacles occur each time a pasted receptacle comes to rest between the magazines, the labels thereby being successively applied upon the previously pasted sides of the receptacles.

After the labels have been applied upon the sides of the receptacles, as last described, the conveyer comes to rest with the receptacles having the labels in position opposite pads 84 operable to press the labels finally against the pasted surfaces of the receptacles. The pads 84 are shown comprising, preferably, flexible pad portions, such as felt 85, carried by blocks 84^a having outwardly projecting rods or pins 86 guided in holes in blocks 87 secured on the bars 53. Pads 84 are shown pressed toward the receptacles by springs 88 bearing against blocks 84^a and 87, pins 89 in the rods 86 limiting movement of the pads toward the receptacles, enabling the latter to be engaged resiliently by the pads, (Fig. 2). When the receptacle A comes to rest between pads 84, with labels adhering to the sides of the receptacle, the bars 53 will approach the receptacles, as before described, and will cause said pads to press the labels against the sides of the receptacles to affix the labels finally thereto with suitable pressure.

The labeled receptacles may be removed from the machine in any suitable manner. We have shown a delivery guide 90 in the form of an open top trough or chute supported at one side of the stopping position of the conveyer with the labeled receptacles. The delivery guide or chute 90 is shown supported upon an upright or brace 91, secured upon table 2, and attached at its receiving end to the adjacent side member 24 by means of brace 92, (Fig. 7). As the labeled receptacles are successively brought to rest by the conveyer opposite the receiving end of the guideway or chute 90 a reciprocative plunger 93 is provided to push the receptacles from the conveyer into said guide or chute. Said plunger is shown in the form of a block 94 preferably having a pad 94 at its end, such as of felt to engage the labeled receptacles, which block is shown carried by rod 95 secured to bar 53 on the side of the conveyer opposite guide 90. The rod 95 is shown attached to block 96 secured upon said bar 53, nuts 97 upon said rod securing the latter to said block in adjusted position, (Fig. 7). Since the labeled receptacles, shown in the form of bottles, lie upon the conveyer in a lengthwise condition it is desired during their delivery to turn them to an upright position, such as illustrated in Fig. 8. For such purpose the guide or chute 90 at the receiving end has an upright side wall 90^a and a wall 90^b having a portion substan-

ti ally horizontally disposed to receive the receptacles from the conveyer in a flatwise condition when pushed from the conveyer by plunger 93. The side members 24 positioned between the guide or chute 90 and plunger 93 are reduced or cut away at 24^b, (Fig. 7), to permit free passage of the plunger and lateral movement of the receptacles from the conveyer into the guide or chute. Beyond the receiving point said wall 90^b is curved gradually to an upright position for a suitable distance until near the delivery portion at 90^c said wall is substantially parallel to and spaced from the wall 90^a, providing a channel between said walls at 90^d through which the receptacles may travel. As the receptacles are successively pushed into the guide or chute 90 they will push one another therethrough, and during their passage along the guide the receptacles will be gradually turned upright on end for delivery in an upright position. The receptacles may be removed from the guide or chute 90 in any suitable way.

In order to keep the receptacles from rising from the conveyer during their travel thereon, and to enable ready access to the receptacles upon the conveyer, a bar 98 is pivotally supported at one end, as at 99, upon one of the uprights 3 and extends at a suitable height over the conveyer, the free end of the bar being received in the upright 3 at the opposite end of the machine, whereby the bar is pivotally retained at a suitable height over the conveyer. The bar 98 as means depending over the conveyer and spaced therefrom to permit free passage of the receptacles A, such means being shown in the form of shoes or strips 100 suspended from bar 98 by hangers 101, which may be secured to the bar by screws 102. The hangers 101 are shown provided with slots 103 receiving said screws, whereby the shoe may be adjusted and retained in desired position over the receptacles on the conveyer. The free end of the bar 98 may be retained attached to upright 3 by means of screw 104 carried by said bar and received in slotted end 3^a of upright 3, (Figs. 1 and 4). One of the shoes or strips 100 is shown located over the conveyer where the receptacles are delivered to the conveyer and where the pasting of the receptacles is effected, and the other of such shoes or strips are shown located over the stopping points of the conveyer where the labels are applied to the receptacles, pressed thereon, and the labeled receptacles delivered to the guide or chute 90, to keep the receptacles from rising from the conveyer when operations are performed on the receptacles. By raising the bar 98 the top run of the conveyer and the receptacles thereon are exposed to permit removal and the replacing of the receptacles, and for other purposes.

When the machine is operated the receptacles to be labeled are supplied to chute 25 and are successively fed upon the conveyer, in manner before described. As the receptacles are carried along by and with the conveyer the sides of the receptacles are supplied with adhesive, the labels are applied to the pasted portions of the receptacles, and the labeled receptacles are pushed by the plunger 10 93 successively into guide or chute 90. The various operations occur simultaneously upon different receptacles by reason of the successive approach and recession of the bars 53 with the operating devices carried there- 15 by, the operations occurring in timed relation to the steps of the conveyer. The labeling operations are entirely automatic and expeditious, since all that is required is to keep the chute 25 supplied with receptacles, 20 and the magazines supplied with labels, and to remove the labeled receptacles delivered from guide 90.

While the machine illustrated is adapted to simultaneously apply labels upon opposite 25 sides of receptacles or containers it will be understood the pasting, label applying and discharging devices may be used upon one side of the conveyer only when it is desired to label one side only of each receptacle.

30 By the term "receptacle" is included articles to be labeled of any desired form of filled or unfilled bottles, cartons, or other containers, or whether they are wrappers, or wrapped articles in the form of packages, or 35 the like.

Changes may be made in the details of construction set forth, within the scope of the appended claims, without departing from the spirit of the invention.

40 Having thus described our invention, what we claim and desire to secure by Letters Patent is:—

1. A labeling machine comprising means to support and propel receptacles, a receptacle for adhesive having distributing means therein, a roller to receive adhesive from the distributing means, a paster operative on the plane of the receptacles, means to move the roller alternately into engagement with the 45 distributing means and with the paster, means to stop the receptacles opposite the paster successively, and means to move the paster toward and from the receptacles to apply adhesive thereto when the receptacles 50 are stopped.

2. A labeling machine comprising means to support and propel receptacles, a receptacle for adhesive having means to distribute the adhesive, a roller to co-operate with said 60 distributor, a rod movably supporting the roller, means to reciprocate the rod to move the roller toward and from said distributor, a paster operative on the plane of the receptacles, means supporting the paster in position 65 to receive adhesive from the roller, means to

stop the receptacles opposite the paster successively, and means to move the paster toward and from the receptacles to apply adhesive thereto when the receptacles are stopped. 70

3. A labeling machine comprising a conveyer for receptacles, means to operate the conveyer step by step, a receptacle for adhesive having means to distribute the adhesive, a paster supported at one side of the 75 conveyer on the plane of the receptacles, means to move the paster toward and from receptacles on the conveyer when the latter is stopped, and an adhesive applying member movably mounted to co-operate with said adhesive distributing means and with said paster between the latter and the receptacle on the conveyer to apply adhesive to the receptacles successively when the conveyer is 80 stopped. 85

4. A labeling machine comprising a conveyer for receptacles, means to operate the conveyer step by step, a receptacle for adhesive having means to distribute the adhesive, a paster supported at one side of the 90 conveyer on the plane of the receptacles, means to move the paster toward and from receptacles on the conveyer when the latter is stopped, an adhesive applying member movably mounted to co-operate with said adhesive distributing means and with said paster between the latter and the receptacle on the conveyer to apply adhesive to the receptacles successively when the conveyer is 95 stopped, and means to move said member from the distributing means to the paster and reversely. 100

5. A labeling machine comprising a conveyer for receptacles, means to operate the conveyer step by step, a receptacle for adhesive having means to distribute the adhesive, a paster supported at one side of the 105 conveyer on the plane of the receptacles, means to move the paster toward and from receptacles on the conveyer when the latter is stopped, an adhesive applying member 110 adapted to co-operate with said distributing means and with said paster and means to move said member from the distributing means to position between the paster and the receptacle on the conveyer to apply adhesive to said paster. 115

6. A labeling machine comprising means to support receptacles, a magazine for labels having an open portion to expose the 120 labels to the receptacles, means to apply adhesive between the labels and the receptacle, said magazine having stops for the labels at the delivery end of the magazine and having feeding means for the labels comprising a plunger co-operative with the labels to cause the endmost label to protrude centrally beyond the stops for engagement with the receptacle, means to move the magazine with the labels toward and from 125 130

the receptacle, and means pivotally carried by the magazine and a separate stop therefor to cause operation of the feeding means after a label is applied to the receptacle.

5 7. A labeling machine comprising means to support receptacles, a magazine for labels having an open portion to expose the labels to the receptacles, means to apply adhesive between the labels and the receptacle, said magazine having stops for the labels at the delivery end of the magazine and having feeding means for the labels comprising a head having a curved face against the labels to cause the endmost label to protrude beyond the stops for engagement with the receptacle, means to move the magazine with the labels toward and from the receptacle, and means pivotally carried by the magazine and a separate 15 stop therefor to cause operation of the feeding means after the label is applied to the receptacle.

20 8. A labeling machine comprising means to support receptacles, a magazine for labels having an open portion to expose the labels to the receptacles, means to apply adhesive between the labels and the receptacle, said magazine having stops for the labels at the delivery end of the magazine and having feeding means for the labels including a rod, a gripper movably supported by the magazine to travel therewith to retain and release the rod, a spring to feed the rod, and means to operate the gripper during its travel with the magazine to release the rod.

25 9. A labeling machine comprising means to support receptacles, a magazine for labels having an open portion to expose the labels to the receptacles, means to apply adhesive between the labels and the receptacle, said magazine having stops for the labels at the delivery end of the magazine and having feeding means for the labels including a rod, a gripper movably supported upon the magazine to retain and release the rod, and a spring to feed the rod, said gripper having a projection, and a stop separate from the magazine in the path of said projection to operate the gripper to release the rod when the magazine moves in one direc-

tion, and means to cause the gripper to grip the rod to retain it from movement when the magazine moves in the opposite direction.

55

10. A magazine for labels having an open delivery portion and stopping means for the labels thereat, feeding means for the labels comprising a rod having a portion to push the labels toward the delivery end of the magazine, means to support and move the magazine with the labels toward and from articles to be labeled, a gripper for said rod, means movably supporting the gripper on the magazine, said gripper having a projection, a stop separate from the magazine co-operative with the projection for operating the gripper to release the rod, means to cause the gripper to grip the rod when moved with the magazine away from the stop, and means to support and operate the magazine relatively to the stop for applying labels to articles.

65

11. A labeling machine comprising a conveyer for receptacles, means to operate said conveyer step by step, bars on opposite sides of the conveyer, means to support and move said bars toward and from the conveyer, pasters on said bars on opposite sides of the conveyer, means to apply adhesive to said pasters and magazines for labels upon said bars on opposite sides of the conveyer to apply labels to adhesive on the receptacles when said bars approach.

75

12. A labeling machine comprising a conveyer for receptacles, means to operate said conveyer step by step, bars on opposite sides of the conveyer, means to support and move said bars toward and from the conveyer, pasters on said bars on opposite sides of the conveyer, means to apply adhesive to said pasters, magazines for labels upon said bars on opposite sides of the conveyer to apply labels to adhesive on the receptacles when said bars approach, and pads upon 90 said bars to finally affix the labels on the receptacles when said bars approach.

85

95 Signed at New York county of New York and State of New York this 17th day of February 1920.

ERNEST D. ANDERSON.
CARL BECKMANN.
